UNITED STATES PATENT OFFICE.

JOSEPH SLEPIAN, OF SWISSVALE, PENNSYLVANIA, ASSIGNEE TO WESTINGHOUSE ELECTRIC & MANUFACTURING COMPANY, A CORPORATION OF PENNSYLVANIA.

PLATE AND METHOD OF TREATING THE SAME.

Application filed April 1, 1922, Serial No. 548,637. Renewed July 29, 1924.

To all whom it may concern:

Be it known that I, JOSEPH SLEPIAN, a citizen of the United States, and a resident of Swissvale, in the county of Allegheny and State of Pennsylvania, have invented a new and useful Improvement in Plates and Methods of Treating the Same, of which the following is a specification.

This invention relates to lightning arresters, more particularly to my new type of lightning arrester which consists fundamentally of stacked plates or disks of high resistance material connected in a suitable manner to an electrical system to be protected.

It is desirable in many cases that the points of contact of the adjacent plates be of very high resistance and I have, therefore, devised a structure of plate and a method of making the same which provides such high resistance contact points. This invention is described in my copending application, Serial No. 548,638, filed April 1, 1922, Plate and a method of treating the same (Case 9674).

In the aforesaid application, I have described a method which consists in stacking plates of high resistance material, placing a relatively small number of thin mica washers therebetween, connecting the stacked plates to an electrical circuit and passing a current therethrough to heat and partially oxidize the surfaces of the plates and thus increase the resistance of the contact points thereof.

In my present invention, I have succeeded in accomplishing the same result in a somewhat different and simplified manner. I first provide a rod of resistance material which generally contains graphite or similar carbonaceous material, carborundum or the like and kaolin. The rod, at a relatively high temperature, is exposed to the air, causing superficial oxidation of the surface thereof, increasing the resistance of said surface, and rendering the same harder than the body of the rod. The rod is then cut transversely of its axis and the plates thus formed are stacked and electrodes applied to the end plates. A current is passed through the stack of plates for a length of time sufficient to heat and partially oxidize the contact points and thus increase their resistance.

In the accompanying drawing constituting a part hereof and in which like reference characters designate like parts,

Fig. 1 is a plan view of a rod of resistance material which has been exposed to the air while in a heated condition;

Fig. 2 is a vertical cross-sectional view thereof taken along the line II—II of Fig. 1;

Fig. 3 is a plan view of a stack of plates clamped between electrodes preparatory to the next step of the treatment;

Fig. 4 is a vertical cross-sectional view thereof taken along the line IV—IV of Fig. 3;

Fig. 5 is a plan view of a completed plate and

Fig. 6 is a vertical cross-sectional view thereof taken along the line VI—VI of Fig. 5 showing the high resistance contact points exaggerated in size to more clearly illustrate a feature of my invention.

Referring particularly to Figs. 1 and 2, I provide a rod 1 of resistor material of any suitable type which is capable of partially oxidizing and is adapted to have its resistance materially increased thereby. Generally, I prepare a mixture of graphite, carborundum, and kaolin which are mixed to the proper consistency with water. The composition is compressed in suitable molds of the desired form and then fired in a furnace. The hot rod is removed from the furnace and exposed to the atmosphere for a relatively short time, whereby the surface 2 of the rod becomes oxidized owing to the oxidation of the carbon of the composition, resulting in a surface of high resistance and relatively great hardness.

The rod is then cut transversely of its longitudinal axis providing plates 3 which are stacked as shown in Figs. 3 and 4. Electrodes 4 and 5 are respectively placed on the end plates of the stack and the assembled structure is clamped in position. A suitable current is passed through the stack preferably by causing a direct current to be maintained for short intervals for a suitable number of times.

This procedure causes heating and oxidation of the contact points of the plates, resulting in oxidation of some of the carbon thereof, leaving a greater proportion of the higher resistance materials in the com-

position, thus greatly increasing the resistance of the contact points of the plates.

Owing to the high resistance of the edges 2 of the plates which are in contact, only 5 a small current can pass therethrough and, therefore, there is very little heating at such high resistance edges. Since there is very little heating at such edges, the contacts remain cool and do not soften, thereby maintaining the disks rigidly spaced. On account of this phenomenon, the contact points 10 6 and 7 of the faces of the plates do not bear any material pressure during the operation and, therefore, any danger of the hot oxidized, high resistance contact points 15 collapsing is avoided.

It will be obvious from the above description of my invention that I am enabled to provide plates of high resistance materials 20 having the exposed surfaces and the contact points of the faces thereof of still higher resistance in a very simple manner. My method lends itself to quantity production and the resulting plates are uniform in 25 their composition.

Although I have described a specific embodiment of my invention, it will be obvious to those skilled in the art that various changes in the details of manipulation of my 30 process may be made without departing from the principles herein set forth. For instance, I may utilize a different composition of material than that which I preferably use and the treatment thereof may be 35 varied to provide the desired results. Instead of exposing the rod of resistance material to the air to increase the resistance of the surface thereof, I may provide a coating on the rod of higher resistance material or 40 I may oxidize the surface of said rod in any other suitable manner.

I claim as my invention:

1. A plate of resistance material, the edges thereof having a higher resistance 45 than the body.

2. A plate of resistance material, the edges and portions of the faces thereof having a higher resistance than the body.

3. A plate of resistance material including a carbonaceous substance, the edges thereof having a higher resistance than the body.

4. A plate of resistance material including a carbonaceous substance, the edges and portions of the faces thereof having a higher resistance than the body.

5. A method of treating plates of resistance material which comprises providing a high resistance portion on said plates, placing said plates in contact and heating the same to raise the resistance of portions of the faces of said plates.

6. A method of treating plates of resistance material which comprises providing a high resistance portion on said plates, plac-

ing said plates in contact and heating the same by passing a current therethrough to raise the resistance of portions of the faces of said plates.

7. A method of treating plates of resistance material which comprises providing a high resistance edge on said plates, placing said plates in contact and heating the same to raise the resistance of portions of the faces of said plates. 70

8. A method of treating plates of resistance material which comprises providing a high resistance edge on said plates, placing said plates in contact and heating the same by passing a current therethrough to raise 80 the resistance of portions of the faces of said plates.

9. A method of treating plates of resistance material which comprises providing a high resistance portion on said plates by oxidizing the same, placing said plates in contact and heating the same to raise the resistance of portions of the faces of said plates. 85

10. A method of treating plates of resistance material which comprises providing a high resistance edge on said plates by oxidizing the same, placing said plates in contact and heating the same to raise the resistance of portions of the faces of said plates. 90

11. A method of making plates of resistance material which comprises providing a rod of resistance material, treating the same to provide a high resistance surface thereon, cutting the same transversely, assembling the plates so formed and heating the same to raise the resistance of the portions of faces of said plates. 100

12. A method of making plates of resistance material which comprises providing a rod of resistance material, treating the same to provide a high resistance surface thereon, cutting the same transversely of the longitudinal axis thereof, assembling the plates so formed and heating the same by passing an electric current therethrough to raise the resistance of portions of the faces of said plates. 110

13. A method of making plates of resistance material which comprises providing a rod of resistance material, oxidizing the same to provide a high resistance surface thereon, cutting the same transversely of the longitudinal axis thereof, assembling the plates so formed and heating the same to raise the resistance of portions of the faces of said plates. 115

14. A method of making plates of resistance material, which comprises providing a rod of resistance material, oxidizing the same to provide a high resistance surface thereon, cutting the same transversely of the longitudinal axis thereof, assembling the plates so formed and heating the same by 125

passing an electric current therethrough to raise the resistance of portions of the faces of said plates.

15. A method of treating plates of resistance material which comprises providing a high resistance portion on said plates, placing said plates in contact so that said plates are maintained in rigid relation by said high resistance portion and heating the same to raise the resistance of portions of the faces of said plates.

16: A method of treating plates of resistance material which comprises providing a high resistance portion on said plates, placing said plates in contact so that said plates are maintained in rigid relation by said high resistance portion and heating the same by passing an electric current therethrough to raise the resistance of portions of the faces of said plates.

17. A method of treating plates of resist-

ance material which comprises providing a high resistance edge on said plates, placing said plates in contact so that said plates are maintained in rigid relation by said high resistance edge and heating the same to raise the resistance of portions of the faces of said plates.

18. A method of treating plates of resistance material which comprises providing a high resistance edge on said plates, placing said plates in contact so that said plates are maintained in rigid relation by said high resistance edge and heating the same by passing an electric current therethrough to raise the resistance of portions of the faces of said plates.

In testimony whereof, I have hereunto subscribed my name this 29th day of March, 1922.

JOSEPH SLEPIAN.
